(57) CLAIM

The ornamental design for a garment, as shown and described.

DESCRIPTION

FIG. 1 is a perspective view of the garment, showing my new design;

FIG. 2 is a front elevational view of the garment shown in FIG. 1;

FIG. 3 is a rear elevational view of the garment shown in FIG. 1;

FIG. 4 is a right side elevational view of the garment shown in FIG. 1;

FIG. 5 is a left side elevational view of the garment shown in FIG. 1;

FIG. 6 is a top plan view of the garment shown in FIG. 1;

FIG. 7 is a bottom plan view of the garment shown in FIG. 1;

FIG. 8 is another perspective view of the garment shown in FIG. 1, showing the garment when worn; and,

FIG. 9 is another perspective view of the garment shown in FIG. 1, showing the garment when worn reversed, in an alternate position.

The even-dashed broken lines in the drawings depict stitching on the garment and form no part of the claimed design. The dot-dot-dashed broken lines in FIGS. 8 and 9, showing portions of the human form, illustrate the design in use and form no part of the claimed design.
